BALL RETURN FOR BOWLING ALLEYS

Quincy A. Edwards, Billings, Mont.

Application August 18, 1938, Serial No. 225,643

1 Claim. (Cl. 273—47)

This invention relates to ball returns for bowling alleys, and has for the primary object the provision of a device of this character which will increase the convenience to a bowler in obtaining balls for bowling and which will conceal from view the balls during substantially their entire travel from the pin end of the alley to the bowling end of said alley so as to not detract or annoy a player while in the act of bowling and will provide a safety factor in that the player or other persons cannot get in the path of the ball during its travel to the ball rack which is substantially hidden from view and conveniently located at the player's end of the alley so that a player may obtain a ball from the rack without interfering with another player in the act of bowling.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a diagrammatical plan view illustrating bowling alleys equipped with ball returns constructed in accordance with the present invention.

Figure 2 is a sectional view taken on line 2—2 of Figure 1.

Figure 3 is a sectional view taken on line 3—3 of Figure 1.

Figure 4 is a rear elevation illustrating the ball rack arranged transversely of the alley and at the player's end of the alley and rearwardly of the player's playing position.

Referring in detail to the drawings, the numeral 5 indicates a series of parallel arranged alleys having at the pin end thereof the usual combined ball and pin pit 6. The players' ends of the alleys 5 are indicated by the character 7. This illustration and brief description is for the purpose of clearly bringing out the present invention wherein ball returns 8 are provided for conveying by gravitation the balls from the pit end to the player's end 7 and wherein a number of alleys will be served by a single ball return.

Each ball return 8 consists of double tracks 9 arranged longitudinally of the alleys and under the flooring of said alleys and each track terminates at the pin ends of the alleys in a laterally disposed portion 10 disposed in a plane thereabove to provide ball receiving portions located in the rear portion of the pit 6 so that the pin setter may readily place balls thereon for gravi-

tation to the main portion of the track 9 which slopes gradually towards the player's end and terminates in a laterally extending and upwardly inclined portion 11. Said portion 11 feeds onto a ball rack 13 extending in an opposite direction to the portion 11 and in substantially parallelism therewith and terminates within a casing 14, as shown at 15. The portions 11 of the companion tracks extend in opposite directions and the racks 13 extend towards each other to 10 terminate within the casing 14. The casing 14 on opposite sides thereof is provided with bumpers 16.

The portions 11 and the racks 13 are located between spaced panels 17 arranged transversely 15 of the players' ends of the alleys and rearwardly of the players' playing positions. The connecting ends of the racks 13 and the portions 11 are confined within casings 18, as shown in Figures 2 and 3, which casings are provided with covers 19 obviating any possibility of a player contacting a ball when passing from the portion 11 to the rack 13. Only a portion of the rack 13 is exposed between the panels 17, as shown in Figure 3, so that a player may readily reach a ball on 20 the rack. The casing 14 is also provided with a cover 20 for concealing the adjacent ends of a pair of racks. From Figure 4 which gives an exterior view of the panels 17 and casings it will be seen that the balls when on the racks 13 are 30 concealed from view except when looking directly downwardly on the balls. Thus it will be seen that the ball racks are located out of the way of the players when in the act of bowling but a player can readily obtain a ball without interfering with another player in the act of bowling.

Referring to Figure 2 it will be seen that the tracks 9 have a considerable dip or inclined portion 21 so that the balls on leaving the slightly inclined portion 10 may gain considerable momentum by traveling downwardly over the portions 21 which is sufficient to carry the ball to the players' ends of the alleys and upwardly of the portions 11 onto the racks 13. Guard strips 22 are provided for maintaining the balls 40 on the portions 11 during their travel upwardly thereof onto the racks 13. The downwardly inclined portions 21 of the tracks are covered and concealed from view, as clearly shown in Figure 2, while the major portions of the tracks are hidden by passing under the alleys or flooring thereof, a suitable trough 23 being provided in the flooring to accommodate the major portions of the tracks, as clearly shown in Figure 3.

It is believed that the foregoing description 55

when taken in connection with the drawings will fully set forth the construction and advantages of this invention to those skilled in the art to which such a device relates, so that further detailed description will not be required.

5 What is claimed is:

A ball return for bowling alleys comprising tracks arranged to parallel alleys and terminating in laterally disposed portions inclined upwardly therefrom, ball racks connecting with said upwardly inclined portions and arranged transversely of the alleys and extending in opposite directions to said upwardly inclined portions, guard panels arranged at opposite sides of the

racks and the upwardly inclined portions of the tracks and having their upper edges disposed in a plane above said racks and upwardly inclined portions of the tracks, casings connecting the ends of said panels and having the connecting ends of the racks and upwardly inclined portions confined therein, a casing receiving adjacent ends of the racks and arranged between the panels, and bumpers carried by the last-named casing and arranged over the racks for checking movement of balls over said racks when received from the upper inclined portions of the tracks.
